UNITED STATES PATENT OFFICE.

GEORGE STOCKER, OF LOS ANGELES, CALIFORNIA.

ATTACHMENT FOR BOOKCASES.

1,260,089.

Specification of Letters Patent. Patented Mar. 19, 1918.

Application filed July 7, 1917. Serial No. 179,206.

To all whom it may concern:

Be it known that I, GEORGE STOCKER, a citizen of the United States, residing at Los Angeles, in the county of Los Angeles and State of California, have invented certain new and useful Improvements in Attachments for Bookcases, of which the following is a specification.

This invention relates to shelf attachments for book cases, and is adapted primarily to provide means whereby heavy and cumbersome books of a size too large for the compartments of the ordinary book case, may be accommodated within the book case in such manner as to minimize space therein, and which enables the books supported thereby to be quickly and easily withdrawn from the book case when needed.

A further object of the invention is to provide a book supporting shelf for use in connection with book cases, which is capable of being readily moved into or out of the book case, and which constitutes an efficient support for holding voluminous works, such as the Bible, dictionary, etc.

A still further object of the invention is to provide a shelf for the accommodation of books which properly supports the books when the shelf is moved into the book case, and which disposes the books when the shelf is moved outwardly in a position most convenient to the reader or user thereof.

Still further objects of the invention reside in providing a shelf for book cases which may be applied to the case when the latter is manufactured, or which may be attached to book cases now in use, which is of extremely simple and inexpensive construction and which is of light weight and yet thoroughly durable, which has its supporting arms so constructed and assembled with the structure as to minimize the opportunity for wear, breakage or derangement, which occupies but comparatively little space within the book case, and which will prove thoroughly practical and efficient in use.

With these objects in view together with others which will appear as the description proceeds, the invention resides in the novel formation, combination and arrangement of parts, all as will be described more fully hereinafter, illustrated in the drawing and particularly pointed out in the claims.

In the drawing:

Figure 1 is a front elevation of a conven-

tional form of book case, to which a movable shelf constructed in accordance with the invention is applied, parts of the book case being broken away to show the manner of application of the shelf thereto,

Fig. 2 is a vertical sectional view on a slightly enlarged scale, taken on the line 2-2 of Fig. 1,

Fig. 3 is a view similar to Fig. 2, and illustrating the shelf moved to operative position, and

Fig. 4 is a fragmentary perspective view of the shelf inverted.

The shelf of my invention is adapted to move horizontally, or substantially so, into and out of the book case, and this shelf supports the books in a position most convenient to be opened and used by a reader. When the shelf has been moved inwardly, all of the parts thereof are confined or lie within the limits of the book case, so that there will be no protruding parts to interfere with the closing of the doors for the book case, or to interfere with the insertion of books in other parts of the case, or the withdrawal of books therefrom. When moved outwardly to its limit, the shelf inclines downwardly, so that the book supported thereby will be disposed at an angle convenient for the user. An improved means is employed for locking the shelf when the latter has been moved outwardly, and the invention is also characterized by means for evenly distributing the weight of the books to various parts of the shelf and to the supporting elements for the latter.

Referring now particularly to the drawing, 5 indicates generally a conventional form of book case, equipped with the hinged doors 6 as shown. This case is provided with the usual number of horizontally arranged shelves 7 for the accommodation of books.

Arranged in the same horizontal plane upon the inner surfaces of the vertical side walls of the book case are track members 8, the said track members being horizontally disposed, and being provided for the purpose of supporting the slidable shelf 9. These tracks may be formed of any suitable material, it being preferred, however, that they be made of relatively thin, light and yet durable metal. The tracks extend from the front edges of the vertical walls to the rear or back of the book cabinet, and are bent downwardly adjacent their rear ends as

at 9', and then extend rearwardly as at 10 in a horizontal direction to the rear wall of the cabinet.

The shelf 9 comprises a flat board equal 5 in width to the distance between the adjacent vertical side walls of the book case, so as to fit snugly between the said walls, and this shelf rests at its ends upon the tracks 8, as shown. The main leaf of the shelf 9 is of 10 a depth equal to that of the book case, and is provided at its forward edge with an upwardly extending rib 10', the said rib being adapted to prevent the books supported by the shelf from sliding forwardly when the 15 leaf is extended. The shelf also includes a pair of narrow leaves indicated at 12 and 13, respectively, the said leaves being hinged together at their adjacent edges as at 14, and one of the said leaves is hinged as at 15 to 20 the main leaf 9. The hinges 14 and 15 are applied to the leaves of the shelf upon the under surface thereof, so as to be capable of swinging downwardly below the main leaf 9 when the shelf is moved into the book case. 25 It will be observed that the forward longitudinal edge of the leaf 12 and the rear edge of the leaf 9 are beveled in such manner that the leaves will be held in the same plane when the shelf is moved outwardly. The 30 combined width or depth of the sections 12 and 13 is equal to the distance between the horizontal track portion 8 and the stop member 10 formed at the rear end of the track, so that when the shelf is moved inwardly, these sections will move downwardly until the rear edge of the section 13 will rest upon the stop portion 10 of the track. When in this position, it is obvious 35 that the weight upon the shelf leaf 9 will be 40 distributed not only to the horizontal portions of the track 8, but also to the stop member or horizontal portion 10 at the rear end of the track.

The shelf leaf 9 is supported in outward 45 position by arms 15' pivoted as at 16 to the inner surfaces of the vertical walls of the book case adjacent the forward edges thereof. These arms are formed of thin metal and are connected with the walls of the book 50 cabinet below the movable shelf. Each of the arms is provided adjacent its outer end with a longitudinally disposed slot 16', and this slot communicates at its outer end with a short angularly disposed slot 17. The 55 slot 17 is so arranged in each arm that when the latter are swung to the limit of their outward movement, the said short slots 17 will be disposed vertically, and to limit the outward swinging movement of the said 60 arms, the latter are cut away as at 18 adjacent their pivots 16, the said cut away portion providing stops which engage the horizontally disposed surfaces of the angle plates 19 secured upon the inner faces of 65 the vertical side walls of the book case.

The ends of the leaf 9 adjacent the forward edges thereof are cut away as at 21, and projecting outwardly from the ends of the leaf in these cut away portions are pins 22, the latter being engaged in the slot 16' 70 in the arms 15'.

From the foregoing it will be seen that when the shelf is moved inwardly, the same will be entirely accommodated within the book case, the hinged leaves 12 and 13 being disposed vertically as shown in Fig. 2 of the drawing. The arms 15' are also disposed in vertical position, and when so positioned are wholly confined within the book case and lie close to the vertical end walls 80 thereof. When it is desired to extend the shelf, the latter may be pulled outwardly, whereupon the same slides along the track-way, moving with it the arms 15'. When the outward swinging movement of the arms 85 15' is limited by the stop surfaces 18, the pins 22 in the ends of the leaf 9 will be disposed at the juncture of the longitudinal and angular slots 16'-17, and the outer end of the shelf when released will move 90 downwardly until limited against further movement by the engagement of the pins 22 in the bottoms of the angular slots 17. This swinging movement of the leaf 9 is permitted by the hinges 14 which connect the leaf 95 12 with the leaf 13, but it will be observed that the leaves 9-12 will be disposed in the same plane. A book placed upon the shelf 9 when inclined will be prevented from slipping beyond the forward edge thereof by 100 the bead or rib 10', and the weight of the book will be evenly borne by the arms 15' at the ends of the shelf, and by the forward edges of the tracks. When it is desired to move the book into the case, the shelf 9 is 105 lifted slightly, whereupon the pins 22 move upwardly in the angular slots 17, and rearward sliding movement of the shelf will cause the latter to travel rearwardly upon the tracks 8; this rearward sliding movement of the shelf causing the arms 15' to rock inwardly upon their pivots 16. When the shelf has been moved to the limit of its inward travel, the end leaves 12 and 13 will have assumed vertical position, as shown in 110 Fig. 2, whereupon the weight of the book upon the shelf will be partially distributed to the horizontal stop member 10.

It is apparent that I have provided a movable shelf for application to book cases which is of extremely simple construction, which is easy and simple of operation, and which will prove thoroughly efficient and practical in the attainment of the ends for 115 which it is designed, and while the present 120 disclosure of the preferred embodiment of the invention, it is obvious that various changes in the minor details of construction and arrangement of parts may be resorted to if desired without departing from the 125 130

spirit of the invention as defined by the appended claims.

What is claimed is:

1. In combination with a book case, a shelf 5 slidable longitudinally into and out of the case, an arm pivoted at one end to said case, means for limiting the outward swinging movement of said arm, the said arm having a longitudinally disposed slot, the said slot 10 being extended angularly at its outer end, and a pin in the outer end of said shelf engaged in said slot and being adapted to rest within said angular portion when said arm is moved to its outward limit.
  2. In combination with a case, a shelf 15 slidable longitudinally into and out of the case, an arm pivoted at one end to said case, the said arm having a longitudinally disposed slot, the outer end of said arm having 20 a laterally extending slot communicating at one end with said longitudinal slot, and a pin in the outer end of said shelf engaged in said slot.
  3. In combination with a case, a shelf 25 slidable horizontally into and out of the case, an arm pivoted at one end beneath said shelf and having a longitudinal slot, a pin in one edge of said shelf at the forward end thereof and engaged in said slot, the said 30 arm being provided adjacent its outer end with an angular slot closed at one end and in communication at its opposite end with one end of said longitudinal slot, and means for arresting the outward swinging movement 35 of said arm when said angular slot is disposed vertically.
  4. In combination with a case, a track in said case, a shelf slidably mounted on said track, a hinged leaf on the inner end 40 of said shelf, an arm pivoted beneath said shelf and being engaged at its outer end with the forward edge of said shelf, and means limiting the outward swinging movement 45 of said arm when the hinges of said leaf have reached the forward edges of said case.
  5. In combination with a book case, trackways arranged horizontally within said book case, a shelf supported at its edges 50 upon said trackway and capable of moving
- into and out of said case, a pair of arms pivoted at their lower ends to said case beneath said shelf, the free ends of said arms extending adjacent the forward edges of said shelf, the said arms being provided 55 with longitudinal slots, pins projecting outwardly from said shelf and engaged in said slot, the said arms having angular slots adjacent their outer ends communicating with the longitudinal slots, means for limiting 60 the outward movement of said arms when said angular slots are disposed vertically, a pair of leaves hinged to the inner portion of said shelf, a stop within said case adjacent the back thereof, the said stop being 65 disposed below said trackways a distance equal to the combined widths of said leaves, and the said shelf being equal in width to the depth of said case.
6. In combination with a cabinet, a track 70 in said cabinet, a stop portion in said cabinet at the rear end of and below said track, a shelf slidable upon said track, and a leaf hinged to the rear end of said shelf and adapted to swing downwardly and to rest 75 upon said stop portion and to support the rear end of said shelf when the latter has moved to the limit of its inward movement.
7. In combination with a cabinet, a track 80 in said cabinet, the said track being curved downwardly and extended rearwardly at the rear end of said cabinet, a shelf slidably mounted upon said track, a pair of leaves hingedly connected together, one of 85 said leaves being pivoted to the rear end of said shelf, the combined widths of said leaves being equal to the distance between said track and said rearwardly extended portion, the said leaves being adapted during the inward movement of the shelf to 90 swing downwardly at right angles to said shelf and to support the rear end of said shelf.

In testimony whereof I affix my signature in presence of two witnesses.

GEORGE STOCKER.
